UNITED STATES PATENT OFFICE

2,299,303

CLAMP FOR BOATBUILDING

Loren P. Burch, Aberdeen, Wash.

Application March 25, 1941, Serial No. 385,081

4 Claims. (Cl. 9—6.5)

This invention relates generally to boat building and particularly to a clamp for use in the construction of boats from ply wood.

The main object of this invention is to construct a clamp for holding chine strips within the forms upon which the boat is constructed, as more fully set forth in my United States Patent No. 2,232,313.

The second object is to construct a clamp of the class described which will hold the chine strips securely in position within the forms or molds and will also permit the easy removal of the boat from the forms.

I accomplish these and other objects in the manner set forth in the following specification as illustrated in the accompanying drawing, in which:

Fig. 1 is a transverse section through a form with the inner chine strip in place and with the clamp omitted.

Fig. 2 is a transverse section through a portion of a mold and a corresponding portion of the boat being formed showing a clamp in a chine holding position.

Fig. 3 is a fragmentary section taken along the line 3—3 in Fig. 2.

Fig. 4 is a fragmentary plan taken along the line 4—4 in Fig. 2.

Fig. 5 is similar to Fig. 2 but showing the clamps in a chine releasing position.

Similar numerals refer to similar parts throughout the several views.

Referring in detail to the drawing, there is shown a form 10 which is reinforced at suitable intervals by ribs 11. The form 10 has slots 12 for the reception of the inner chine strips 13. A section of ply wood or other material 14 is bent around the form 10, usually in the presence of moist heat.

The function of the clamp which I am about to describe, is to hold the strip 13 securely in place until it is desired to remove the boat 14 from the form 10. In order to make this possible, after the strip 13 is secured to the boat 14, it is necessary to relieve the slots 12 along the edge 15 as indicated in order to permit the boat 14 to be moved parallel to the vertical sides 16.

Referring particularly to the clamp, it will be seen to consist of a fixed side 17 which is secured to the angle bracket 18 by the bolt 19, and the movable side 20 which is provided with a slot 21 to receive the bolt 22 which also passes through the angle bracket 18.

Sides 17 and 20 are provided with strip engaging jaws 23 and 24 which are adapted to engage

opposite sides of the strip 13. The ends 25 and 26 of the sides 17 and 20 can be urged apart by the clamping screw 27 which is threaded through the side 20 and is provided with a hand crank 28 on one end and a washer 29 near its opposite end 30 which is free to slide in the slot 31 formed in the edge of the side 17.

The angle bracket 18 is secured to the form 10 by means of bolts 32 or in any other convenient manner.

The operation of the device is as follows:

Assuming that the strips 13 are in place in the respective slots 12 and that the shell or body of the boat 16 has been formed into the position as shown in Figs. 2 and 5, it is desirable to hold the strips 13 fixed in their respective slots 12. In order to do this one need merely to turn the crank 28 in a direction to urge their ends 25 and 26 apart which naturally urges the jaws 23 and 24 together, clamping the strip 13 between same and thereby facilitating the fastening of the strip 13 to the side 14 or to a second chine strip which is placed on the outer side of the boat 16.

When the boat 16 is ready to be removed from the form 10, it is only necessary to release the side 20 by reversing the movement of the crank 28 and permitting the side 20 to move downwardly to the position shown in Fig. 5. That is, permitting the boat to be moved vertically carrying with it the attached chine strips 13.

Obviously the particular details employed in the construction of this clamp are of lesser importance than the fact that the use thereof permits the free movement of the boat upwardly on release, and requires only a small amount of material in order to satisfactorily accomplish the desired purpose during the chine stripping operation.

I claim:

1. A clamp for chine strips in ply wood boat building consisting of a slotted form adapted to hold a chine strip and a pair of jaws mounted in said form adapted to hold the chine strip, one of said jaws being longitudinally movable for the purpose of permitting the chine strip to be moved diagonally off of its slot.

2. In a clamp of the class described, the combination of a form for the interior of a boat, said form having slots formed therein for the reception of chine strips, a fixed jaw registering with one side of a chine strip slot and a pivotally and slidably mounted jaw adapted to engage the opposite side of a chine strip disposed within said chine strip slot and means for urging the chine engaging end of the jaws together by urging the

opposite ends thereof apart, consisting of a crank driven screw threaded through one of said jaws and slidably engaging the other jaw.

3. The apparatus as described in claim 2 characterized by having the sides of a chine strip slot beveled to permit the vertical movement of a chine strip as it is being removed from the form.

4. In a device of the class described, the combination of a curved form for forming ply wood boats, the curved portion of said form having a slot formed therethrough for the reception of a chine strip, a transverse opening formed through

the curved portion of said form having a pair of substantially parallel jaws projecting therethrough adapted to hold a chine strip between same, one of said jaws being fixed and the other pivoted in a manner to afford slidability to said jaws as well as to vary its angularity with relation to the opposite jaw for the purpose of changing the distance between the strip engaging jaws, and a screw between the opposite ends of said jaws adapted to urge the portions thereof apart.

LOREN P. BURCH.
